(57) **CLAIM**

(**) Term: **14 Years**

The ornamental design of an apparatus for leak testing and refilling automotive cooling systems using vacuum, as shown and described.

(21) Appl. No.: **29/125,917**

DESCRIPTION

(22) Filed: **Jul. 5, 2000**

FIG. 1 is a top view of the apparatus for leak testing and refilling automotive cooling systems using vacuum.

Related U.S. Application Data

FIG. 2 is a bottom view of the apparatus for leak testing and refilling automotive cooling systems using vacuum.

(63) Continuation-in-part of application No. 29/115,038, filed on Dec. 6, 1999, now Pat. No. Des. 431,007.

FIG. 3 is a left side view of the apparatus for leak testing and refilling automotive cooling systems using vacuum.

(51) **LOC (7) Cl. 10-04**

FIG. 4 is a right side view of the apparatus for leak testing and refilling automotive cooling systems using vacuum.

(52) **U.S. Cl. D10/101**

FIG. 5 is a front view of the apparatus for leak testing and
